UNITED STATES PATENT OFFICE.

VICTOR C. THOMPSON, OF LOS ANGELES, CALIFORNIA.

DESIGN FOR A DOLL.

Application filed April 4, 1925. Serial No. 13,022. Term of patent 3½ years.

To all whom it may concern:

Be it known that I, VICTOR C. THOMPSON, a citizen of the United States, residing at Los Angeles, in the county of Los Angeles and State of California, have invented a new, original, and ornamental Design for Dolls, of which the following is a specification, reference being had to the accompanying drawing, forming part hereof.

In the drawing,

I claim:

The ornamental design for a doll as shown.

VICTOR C. THOMPSON.

Witnesses:

ETHEL PECK,
J. SHUTT.
